UNITED STATES PATENT OFFICE.

ARTHUR MAEHLER, OF CHICAGO, ILLINOIS.

MEANS FOR VENTILATING DRYING OVENS.

Application filed July 19, 1922. Serial No. 576,056.

To all whom it may concern:

Be it known that I, ARTHUR MAEHLER, a citizen of the United States of America, residing at Chicago, in the county of Cook 5 and State of Illinois, have invented a certain new and useful Improvement in Means for Ventilating Drying Ovens, of which the following is a specification.

This invention relates to that class of internally heated drying and enameling ovens in which means are provided for a circulation through and removed from the oven chamber of the contained air mixed with vapors generated in an operation of the oven. 10

The present improvement has for its object, to provide a structural formation and combination of the ventilation parts and features, by which an effective ventilation of the oven chamber is attained, and with 15 which the removal of the heated air charged with vapor generated in the operation of the oven, can be changed from one portion to another of the oven chamber at the will of the operator, without any varying or excessive load being imposed on the motor by which the air moving means is impelled. With the construction a much smaller motor is needed than that used with ordinary 20 systems of ventilation in drying and enameling ovens, with the attainment of very effective results and in an economical manner, all as will hereinafter more fully appear.

In the accompanying drawing:—

Fig. 1, is a longitudinal sectional elevation on line 1—1, Fig. 2, of a drying and enameling oven embodying the invention.

Fig. 2, is a transverse section on line 2—2, Fig. 1, illustrating the use of a gas heating means.

Fig. 3, is a fragmentary transverse section illustrating the use of an electric heating means.

Like reference numerals indicate like parts in the different views.

Referring to the drawings, 1 designates the roof portion, 2 designate the end walls, and 3 designate the side walls of the oven casing or housing, of any usual detail construction and adapted to provide a closed 45 operating chamber, preferably of a rectangular shape as shown.

4 designate heaters, which may be of the ordinary tubular gas fired type illustrated in Fig. 2, or the electric heater type illustrated in Fig. 3, which are arranged adjacent to and parallel with the side walls 3 of the

oven, and preferably in spaced relation to said walls as shown in Figs. 2 and 3.

5 designate counterpart pairs of inlet ducts arranged between the heaters 4 and the oven side walls 3. Each inlet duct is of an L or angular form, having a horizontal branch 5', as shown in Figs. 1 and 2, or 5''' as shown in Figure 3 extending out through an oven end wall 2, and a vertical branch 5'' 60 extending upwards between the heater 4 and a side wall 3 to near the top of the oven chamber and opening horizontally into the same. In the preferred construction shown in Fig. 1, the vertical branches 5'' are in 65 spaced relation to each other in order to attain a discharge of the incoming air, into the oven chamber adjacent to the upper four corners of the same. The air passing through the ducts 5 being exposed to a pre-heating operation from the adjacent heaters 4.

6 designates a pair of outlet ducts for the mixed vapor and heated air of the oven chamber. Each of said ducts is of an L or 70 angular form, having a vertically arranged branch 6' arranged adjacent to an end wall 2 of the oven and opening into the bottom portion of the oven chamber, and a horizontal branch 6'' arranged adjacent to the 75 oven roof 1 and extending to the center of the oven for connection in common with a companion branch 6'' of the other outlet duct, to a vertical trunk 7 arranged centrally in the oven roof 1 and having connection with 80 the intake end of an exhaust fan now to be described.

8 designates an exhaust fan, preferably arranged above the oven roof, with its intake connected to the aforesaid trunk 7 and 85 associated outlet ducts 6. The outlet or discharge of the fan 8 is connected to a pipe or conductor 9 which extends a distance upwardly into a tubular stack 10, said stack in turn extending to the outer atmosphere 100 or to the smoke stack of the building. In the present improvement the lower end of the tubular stack 10 has a closed formation and is provided with a supplementary connection with the top portion of the oven 105 chamber by means as follows:—

11 designates ducts having connection with the lower end of the stack 10, at opposite sides of the same, and extending down through the oven roof 1 to have communication with the upper portion of the oven 110 chamber.

With the above described arrangement of parts, the discharge from the fan 8 through the pipe or conductor 9 is adapted to create a suction in the stack 10, so that when the 5 ducts 11 are unobstructed, the upper strata of the aeroform contents of the oven chamber is drawn off and discharged into the outer atmosphere in an even and constant manner. With the ducts 11 in an obstructed 10 or closed condition, no such removal of the upper strata of the oven contents takes place, and the control of said ducts is effected by means as follows:—

12 designates dampers, preferably of the 15 swinging type shown, arranged in the ducts 11, with their pivot shafts carrying crank arms 13 exterior of the walls of said ducts, and connected together by a push and pull rod 14, convenient of access on the part of 20 the operator, and adapted to effect a simultaneous opening and closing of the valves or dampers.

Having thus fully described my invention, what I claim as new and desire to secure by Letters Patent, is:—

1. In an oven of the type described, the 25 combination of a closed oven casing, heating means arranged in said casing, an inlet duct for introducing air into the upper portion of the interior of said casing, an outlet duct adapted to take air from the lower portion of the interior of said casing, an exhaust fan having its intake connected with said outlet duct, a hollow stack closed at its lower end, a pipe arranged within the lower end of said stack and connected with the outlet of the fan, a duct connected to said stack at one end and at the other end to the upper portion of the interior of the 30 casing, and a damper arranged in said duct.

2. In an oven of the type described, the 35 combination of a closed oven casing, heating means arranged at the respective sides of the interior of said casing, a plurality of inlet ducts having vertical branches arranged intermediate of the heaters and the side walls of the casing and adapted to introduce air into the upper portion of the interior of the casing, a plurality of outlet ducts arranged at the respective ends of the casing and adapted to take air from the lower portion of the interior of the casing, an exhaust fan having its intake connected to the outlet ducts by a vertical trunk 40 common to both outlet ducts, a hollow stack closed at its lower end, a pipe arranged in the lower end of said stack and connected to the outlet of the fan, a plurality of supplementary outlet ducts connected at one end to the lower end of said stack and at the other end with the upper portion of the interior of the 45 casing, and dampers controlling the outlet ducts.

3. In an oven of the type described, the

combination of a closed oven casing, heating means arranged at the respective sides of the interior of said casing, a plurality of inlet ducts having vertical branches arranged intermediate of the heaters and the side walls of the casing and adapted to introduce air into the upper portion of the interior of the casing, a plurality of outlet ducts arranged at the respective ends of the casing and adapted to take air from the lower portion of the interior of the casing, an exhaust fan having its intake connected to the outlet ducts by a vertical trunk common to both outlet ducts, a hollow stack closed at its lower end, a pipe arranged in the lower end of said stack and connected to the outlet of the fan, a plurality of supplementary outlet ducts connected at one end to the lower end of said stack and at the other end with the upper portion of the interior of the casing, and dampers arranged in said supplementary ducts and connected together for simultaneous operation.

4. In an oven of the type described, the 50 combination of a closed oven casing, heating means arranged at the respective sides of the interior of said casing, counter part pairs of inlet ducts of an L form having vertical branches in longitudinal spaced relation and adapted to introduce air into the upper portion of the interior of the casing, a plurality of outlet ducts arranged at the respective ends of the casing and adapted to take air from the lower portion of the interior of the casing, an exhaust fan having its intake connected to the outlet ducts by a vertical trunk common to both outlet ducts, a hollow stack closed at its lower end, a pipe arranged in the lower end of said stack and connected to the outlet of the fan, a plurality of supplementary outlet ducts connected at one end to the lower end of said stack and at the other end with the upper portion of the interior of the 55 casing, and dampers controlling the outlet ducts.

5. In an oven of the type described, the 60 combination of a closed oven casing, heating means arranged at the respective sides of the interior of said casing, a plurality of inlet ducts having vertical branches arranged intermediate of the heaters and the side walls of the casing and adapted to introduce air into the upper portion of the interior of the casing, a plurality of outlet ducts arranged at the respective ends of the casing and adapted to take air from the lower portion of the interior of the casing, and an exhaust fan having its intake connected with the aforesaid outlet trunks.

Signed at Chicago, Illinois, this 18th day of July 1922.

ARTHUR MAEHLER.
